UNITED STATES PATENT OFFICE.

SIDNEY E. THOMPSON, OF WEST ENGLEWOOD, NEW JERSEY, ASSIGNOR TO COPELAND & THOMPSON, INC., OF NEW YORK, N. Y., A CORPORATION OF NEW YORK.

DESIGN FOR A PLATE OR SIMILAR ARTICLE.

Application filed March 23, 1925. Serial No. 12,845. Term of patent 14 years.

To all whom it may concern:

Be it known that I, SIDNEY E. THOMPSON, a subject of the King of Great Britain, and a resident of West Englewood, in the county of Bergen and State of New Jersey, have invented a new, original, and ornamental Design for Plates and Similar Articles, of which the following is a specification, reference being had to the accompanying drawing, forming a part thereof.

The single figure of the drawing is a plan view of a plate showing my new design. It will of course be understood that the design is repeated over the entire surface of the plate as indicated in the drawing.

I claim:

The ornamental design for a plate or similar article, as shown.

SIDNEY E. THOMPSON.
